UNITED STATES PATENT OFFICE.

LINNAEUS E. BAKER, OF FORT WAYNE, INDIANA, ASSIGNEE TO WAYNE COMPANY, OF FORT WAYNE, INDIANA, A CORPORATION OF INDIANA.

PUMP PISTON.

Application filed July 3, 1923. Serial No. 649,235.

My invention relates to pistons for reciprocating pumps.

The combination constituting this invention forms a piston light in weight, strong, durable, inexpensive, which takes a small amount of room in the pump head and requires a very small amount of machine work. The cup leather is so formed and supported as to prevent its being crowded against the walls of the cylinder in such a manner as to cause excessive friction. The top and bottom plates and the spring are preferably made of sheet metal, and the spacer between the two of tubing, and when the top and bottom plates are so punched and drawn a cheap and sturdy frame-work is formed, with enclosing space for the valve and valve weight.

My invention is illustrated in the accompanying drawings, in which,

20 Figure 1 shows the piston and the attendant part of the piston rod; substantially one-quarter of the piston being cut and broken away to show the same in axial section, and

25 Fig. 2 is a top plan of the same with a part equal approximately to a segment of $\frac{1}{6}$ of the top plate broken away to show a portion of the weight and the spring, another like segment of the weight and spring and superimposed parts broken away to show 30 the valve leather and piston leather, and another like segment of the valve leather, piston leather and superimposed parts broken away to show the bottom plate.

35 Referring now to the drawings, a disc bottom plate A preferably punched from sheet metal has its peripheral edge bent upwardly to better support a cup leather G. This bottom plate has a plurality of bolt holes α , a plurality of ports α^1 , and an axial hole α^2 for the piston rod D.

Above this bottom plate A and co-axial with it is a tubular spacer C adapted to make a slip fit over the piston rod D.

40 A disc valve leather E is pierced axially to seat over the spacer C upon the top of the bottom plate A, normally closing the ports α^1 , and a valve weight F which fits loosely over the spacer C rests upon the valve leather tending to hold it to its seat.

45 An upwardly cupped disc piston leather G rests upon the outer part of the top of the lower plate A, has a plurality of bolt holes γ adapted to register with the bolt holes α .

50 A disc spring S upwardly cupped and having at its periphery fingers s adapted to

exert a resilient pressure upon the inside surface of the cupped portion of the piston leather G tending to hold it at all times in contact with the cylinder wall (not shown).

A circular piston top plate H, preferably 60 punched from sheet metal, is formed with its central portion extending upwardly in the form of a truncated cone, and has a plurality of bolt holes h registering with holes γ and α , a plurality of liquid passages h^1 and an axial 65 hole h^2 for the piston rod D. The top plate H has its peripheral edge cupped upwardly in such a manner as to leave a space between it and the spring fingers s when the top plate is pressed down into position for 70 being assembled upon the spring S towards its periphery and upon the spacer C at the center.

The piston rod D with nut d above and nut d^1 below holds the piston members 75 securely together at the center, and bolts B each with a nut b hold the piston members securely together towards the periphery. h^3 are vent holes.

Obviously many changes may be made in 80 the device without departing from the spirit of my invention.

I claim as my invention and desire to secure by Letters Patent of the United States:—

1. A piston having a top and bottom plate shaped to form a chamber between them, a flexible disc valve in said chamber, and independent means tending to keep said valve closed. 90

2. A piston having a top and a bottom plate shaped to form a chamber between them, a flexible disc valve in said chamber, an independent weight tending to keep said valve closed, and a piston leather between 95 said top and bottom plates at the periphery of the piston.

3. A piston having a top and a bottom plate shaped to form a chamber between them, a single flexible disc valve in said 100 chamber, an independent weight tending to keep said valve closed, a piston leather between said top and bottom plates at the periphery of the piston, and a spring tending to hold said piston leather in contact with the wall of the cylinder in which said piston operates.

4. A piston adapted to be secured to a piston rod, having in combination, a bottom plate, a top plate having an upwardly bulg- 110

ing central portion to form a chamber between said top and bottom plates, means for holding said top and bottom plates in spaced relation to each other, liquid passages in said top plate and ports in said bottom plate, a valve leather adapted to close saids ports, a valve weight adapted to seat upon said valve leather, a cupped piston leather seated upon the lower plate at its periphery, a plate spring adapted to seat between said piston leather and the top plate and to tend to press the cupped portion of the piston leather outwardly, and means for securing the parts together to form a piston.

5. A piston adapted to be secured to a piston rod, having in combination, a bottom plate cupped upwardly at its periphery and of such diameter as to escape contact with the cylinder wall, a top plate cupped upwardly at its periphery and having an upwardly bulging central portion to form

a chamber between said top and bottom plates, an axially placed sleeve for the piston rod, adapted to hold said top and bottom plates in spaced relation to each other, liquid passages in the top plate, ports in said bottom plate, a valve leather guided by said sleeve adapted to close said ports, a weight guided by said sleeve adapted to seat upon said valve leather, an upwardly cupped piston leather seated upon the lower plate at its periphery, a fingered plate spring adapted to seat upon said piston leather and to tend to press the cupped portion of the piston leather outwardly, the top plate adapted to allow movement of the spring fingers, and a plurality of bolts toward the periphery of said plates holding the top and bottom plates, piston leather and spring securely together.

In testimony whereof I have hereunto set my hand.

LINNAEUS E. BAKER.
